GEORGE HEITLER

Inventor

By his Attorney Julian J. Mittal

UNITED STATES PATENT OFFICE.

GEORGE HEITLER, OF NEW YORK, N. Y.

WEDGE ATTACHMENT FOR SHOES.

Application filed September 9, 1921. Serial No. 499,416.

To all whom it may concern:

Be it known that I, GEORGE HEITLER, a citizen of the United States, and resident of New York, in the county of New York and 5 State of New York, have invented certain new and useful Improvements in Wedge Attachments for Shoes, of which the following is a specification.

The object of this invention is to provide 10 a wedge-like attachment to the inside of shoe soles whereby the foot of the wearer will be raised at the outside and lowered at the inside thereby throwing the weight of the wearer more to the inside than it is done 15 when wearing shoes of the usual make.

Another aim of this invention is to provide such a wedge-like attachment which while throwing the weight of the wearer towards the inside of the foot will also provide 20 certain lowered portions at the inside underneath the big joint and the big toe of the foot thereby giving said joint and big toe a comfortable room and resting place inside of the shoe and contribute towards an 25 equal distribution of the pressure on the whole surface of the foot.

A further object of this invention is to provide similar wedge-like attachments under the outsides of the heels of the wearer 30 which will relieve the heel portion of the foot of its usual tendency of pressing the shoe outwardly. At the same time my device may provide a hollow portion under the central bone of the heel in the shoe, 35 relieving this bone of the relatively excessive pressure which it usually bears in the shoes of present make and distributing the weight over the whole surface of the heel. In cases where it seems to be necessary, 40 my device may be combined with a simple arch supporter, as will be seen in one of the embodiments of my device shown in the accompanying drawing and described hereinafter. My purpose also is to provide such 45 a device in such a form and make as will be easy to apply in any shoe of standard make, easily removed or exchanged, and which will be easily and cheaply manufactured.

50 With these and other objects in view my invention consists of a piece of leather or other material cut and formed to suit said objects, fitting into the inside of the shoe of the wearer, having wedge-like attachments underneath fastened to it and having

nails or other means to apply it into said shoe and keep it in place.

In the accompanying drawings, Fig. 1 is a top view of my device shown in the form contemplated by me to be the ordinary usual 60 one, showing with dotted lines the wedge attachment applied underneath thereof and showing with dash and dot lines the complete outlines of the shoe soles to which it is attached.

Figs. 2, 3, 4 are cross sectional views of Fig. 1 taken on the lines A—A, B—B, C—C, respectively.

Fig. 5 is a similar view to Fig. 1 of my device with an arch supporter combined 70 with same. Figs. 6, 7, and 8 are cross sectional views of Figure 5 taken on the lines D—D, E—E, F—F, respectively. Fig. 9 is a cross sectional view taken on the line G—G of Fig. 5.

Fig. 10 is a similar view to Figs. 1 and 5, showing my device with a full heel portion. Figs. 11, 12, and 13 are cross sectional views similar to the previous ones taken on the lines H—H, I—I, J—J, respectively. Fig. 80 14 shows my device in top view in a fuller form and Figs. 15, 16, 17 are cross sectional views similar to the previous ones and taken on the lines K—K, L—L, and M—M, respectively, of Fig. 14.

Referring more closely to the drawings, 85 1 indicates the main body of my device made of leather or other suitable material and cut into a shape to fit the style of the shoe in view. The front and back parts of the device are made generally heavier at the outside and thinner towards the inside as shown in Figs. 2 and 4, while the center part may be left somewhat thinner but of even cross section, as at Fig. 3. Underneath the outer 90 portion at the front of the foot and at the heel, I apply the wedge-like pieces 2, 2. The general thinning of my device towards the inside and the wedge-like attachments 2, 2 will throw the foot and the weight of the 95 wearer towards the inside of the shoe. The inside portion of the shoe sole is left unchanged and in the front part around the space marked with the letter a it remains lowered and gives free space to the big toe 100 and the big joint of the foot. The action of this device will lead to the more equal distribution of pressure, and more straight walk, will keep the foot in a natural position, relieve its most sensitive parts in the 105 110

front and give them a comfortable space and finally will keep the shoe in a perfect form and make it similar to a custom made shoe. To apply my device easily into any 5 shoe, I provide two nails 3, 3 in the front and back parts of same into the wedge-like attachment so that my device will be easily inserted into any shoe and kept in a fixed position while the nails will not irritate the 10 foot of the wearer since they are covered by the original body of my device.

In Fig. 5 another form of my device is illustrated similar to the one shown before with the exception that it has an arch supporting extension 4. This extension has a generally curved upper surface, as shown in Fig. 9, while its cross section is made of a wedge-like form; in the reverse direction to wedges 2, 2 and as shown in cross section at Fig. 7. This arch support and reverse wedge will help to throw the weight carried around the arch more to the outside of the foot thereby supporting and relieving a possibly weakened arch of the wearer. 15

20 The device shown in Fig. 10 is again similar in the main idea to the previous ones with the exception that the heel portion of the same is kept full, thereby insuring a firm position for the back part of my device without the use of a second nail. Fig. 25 14 illustrates a form of my device very similar to that shown in Fig. 10 with the exception that its form is made more full in the back portion of same for reasons explained before. This last form of my de-

vice omits the second wedge attachment under the heel as it is meant for such cases where only the front part of the foot is desired to be thrown inwardly. Both of the last two forms show a hollowed shape underneath the heel as shown at 5 and 6 of Figs. 13 and 17, respectively; said hollow serves the purposes discussed hereinbefore, namely the relieving of the central bone of the heel and distributing part of the pressure on the fleshy portions of the heel. 40 45

Having thus described my invention what I claim as new is:

As a new article of manufacture, a wedge-like attachment for the inside of the soles of boots or shoes, consisting of a piece of leather or other material, generally following the contour of the outside of the sole of said boot or shoe but covering a portion of said sole only, generally being of a 50 heavier cross section at the outside than towards the inside, two-wedge-like attachments applied at the outside underneath the front and back portions of said piece of leather or other material, pointing inwardly, 55 and an extension underneath the arch portion of the foot, having a curved convex upper surface and a wedge-like cross section pointing the reverse direction to that of said two wedge-like attachments. 60 65

Signed at New York, N. Y., in the county of New York and State of New York, this 31st day of August A. D. 1921.

GEORGE HEITLER.
